(57) **CLAIM**

The ornamental design for an earhook for earphone as shown and described.

DESCRIPTION

FIG. 1 is a front, top, and left side perspective view of an earhook for earphone, showing a first embodiment of the claimed design;

FIG. 2 is a front view of the first embodiment;

FIG. 3 is a back view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a rear, bottom, and right perspective view thereof;

FIG. 9 is a front, top, and left side perspective view of the first embodiment, in which an earphone is installed in a state of use;

FIG. 10 is a front, top, and left side perspective view of an earhook for earphone, showing a second embodiment of the claimed design;

FIG. 11 is a front view of the second embodiment;

FIG. 12 is a back view of the second embodiment;

FIG. 13 is a left side view of the second embodiment;

FIG. 14 is a right side view of the second embodiment;

FIG. 15 is a top view of the second embodiment;

FIG. 16 is a bottom view of the second embodiment;

FIG. 17 is a rear, bottom, and right side perspective view of the second embodiment; and,

FIG. 18 is a front, top, and left side perspective view of the second embodiment, in which an earphone is installed in a state of use.

The broken lines shown in FIGS. 9 and 18 depict environment and form no part of the claimed design.

1 Claim, 14 Drawing Sheets
